UNITED STATES PATENT OFFICE.

GEORGE WASHINGTON JONES, OF CHICAGO, ILLINOIS.

INTERNAL-COMBUSTION ENGINE.

1,128,685.

Specification of Letters Patent. Patented Feb. 16, 1915.

Application filed March 10, 1913. Serial No. 753,357.

To all whom it may concern:

Be it known that I, GEORGE WASHINGTON JONES, a citizen of the United States, and a resident of Chicago, in the county of Cook and State of Illinois, have invented certain new and useful Improvements in Internal-Combustion Engines; and I do hereby declare that the following description of my said invention, taken in connection with the 10 accompanying sheet of drawings, forms a full, clear, and exact specification, which will enable others skilled in the art to which it appertains to make and use the same.

This invention has general reference to 15 internal combustion engines; in particular, to that type known as two cycle engines, and it consists, essentially, in the novel and peculiar combination of parts and details of construction, as hereinafter first fully set 20 forth and described and then set forth in the claim.

In the drawings already referred to, which serve to illustrate my said invention more fully, Figure 1 is a vertical section of 25 a two cycle engine embodying my invention, showing the working piston thereof at the beginning of its stroke; Fig. 2, a similar section showing the piston at approximately its lowest position; Fig. 3, a like section, 30 illustrating the piston in a position shortly after the beginning of the up or return stroke; Fig. 4, a plan of the engine; Fig. 5, a section through the inlet valve located on the cylinder head of the engine, and Fig. 6, 35 a section through a secondary piston embodied in my invention.

Like parts are designated by corresponding characters and symbols of reference in all the figures of the drawing. 40 The aim and object of my invention is the production of a two cycle, internal combustion engine in which the undesirable qualities common to that type of motor are eliminated, such, as for instance, the necessity 45 for a closed, tight crank case, to maintain what is known as "crank case compression," the liability of premature explosions, and the frequent mixing of the gases of combustion with the incoming charge.

In practising my invention, the foul or exploded gases are forced out of the cylinder by means of a secondary piston located in the engine cylinder, above or behind the working piston therein, and, which, when in 50 its upper position, is directly adjacent the cylinder head of the motor, with but very

little clearance between. Said secondary piston is at rest during approximately 135 degrees of crank revolution on the downward stroke of the working piston, at which point the said working piston has half uncovered the exhaust port in the cylinder. 60 As the working piston passes the above mentioned point, the secondary piston is caused to rapidly descend to a point half covering the exhaust port, during which time the crank has advanced to 225 degrees of revolution; the working piston completed its down stroke, and begun its return, practically meeting the secondary piston. 65 Before actual contact of the two pistons has taken place, however, the secondary piston has been caused to begin its return stroke at an accelerated velocity, so as to reach its highest point approximately 30 degrees in 70 advance of the working piston. 75

The cylinder head of the motor is provided with a typical spring seated inlet valve for the explosive mixture, which valve is caused to open as a result of the atmospheric rarefaction taking place as the downward stroke of the secondary piston, thereby admitting the said mixture into the cylinder in the space between the cylinder head and the said secondary piston. This 80 piston is provided with one or more spring seated valves, the opening of which is caused at the beginning of the return stroke of said piston, thereby permitting the transfer of the mixture from above the secondary 85 piston to the space between the two pistons. It will thus be observed that a positive ejection of the exploded gases will have taken 90 place before the fresh charge is admitted between the two pistons, thereby eliminating any possibility of an affected mixture. During the return stroke of the two pistons, 95 it is evident that an equilibrium of compression will exist between the same and between the secondary piston and cylinder head, so that the secondary piston is brought to a state of rest at top stroke under compression and without jar.

In order to render the operation of the secondary piston practicable, and to prevent possible premature ignition of the charge while transferring through the valve or valves in said piston, resulting from the heat of compression, I have provided means to include the secondary piston in the water cooling system of the motor, so that a circulation of water takes place throughout the 100 105 110

same and around the valves therein, in order that isothermal compression of the charge may be approached.

For a fuller understanding of the details 5 of my invention, I now refer to the sheet of drawings, in which—

A is the motor or engine cylinder, having outer and inner walls 1 and 2, respectively, with an annular water circulating chamber 3 therebetween. Properly positioned in said 10 side walls 1 and 2, is formed a boss 4, the interior of which is cored out to provide an exhaust port 5, having a threaded opening 6, to which the usual exhaust pipe or muffler (not shown) may be attached. At the 15 lower extremity of cylinder A, is provided a threaded opening 7, for ingress of a cooling medium to the annular chamber 3, and, near the upper end of said cylinder is 20 formed a pocket 8, communicating with the interior of the same, for the reception of a spark plug 9, which plug is connected by wires 10 and 10^a to suitable timing mechanism not shown.

25 The lower end of cylinder A is fastened to a base or crank case B, which crank case is provided on its side walls 13, with the usual journal boxes or main bearings to support for rotation, a crank shaft 10. On the 30 exterior of said base or crank case, are integrally formed a pair of journal brackets 11 and 11^a, for the reception of an oscillatable shaft 12, for purposes hereinafter described.

35 Closing the upper end of the cylinder A is a cylinder head C, composed of outer and inner walls 14 and 15, and, therebetween, a water chamber 16, which is in communication with the annular water chamber 3 in 40 the cylinder A. Centrally of this head is provided a circular opening for the passage therethrough of a hollow piston rod 17, a tight joint being maintained around said rod by means of a stuffing box 18 and a 45 gland 19. The lower end of this piston rod is securely fastened to a secondary piston 20, shown in detail in Fig. 6. As seen, this piston has annular, intercommunicating, interior water passages 21 and 21^a, connecting, 50 by means of outlets 22 and 22^a, to the interior 23 of the hereinbefore mentioned hollow piston rod 17.

Passing through secondary piston 20 are 55 a suitable number of round openings 24, the lower ends of which are beveled to produce seats for valves 25, which valves are provided with studs or stems 26 and springs 27 supported by cross bars 28 within said openings 24. The object of the springs 27 is to 60 maintain the valves 25 in closed position and against their seats.

The upper or free end of hollow piston rod 17 enters a cylindrical member 28, which 65 has a stuffing box 29 at its lower end encircling said rod, and a threaded opening

30 at its upper extremity. Said member 28 is supported a proper distance above cylinder head C, axially with rod 17, by means of brackets 31 and 32, the latter of which has an internal water passageway 33, communicating with the interior of member 28 at its upper end and with the water chamber 16 in head C at its lower extremity. Said member 28, brackets 31 and 32, and cylinder head C, are formed integral in the 70 process of casting in actual practice. Attention is now called to the fact that the opening 7 at the lower end of the cylinder A and the opening 30 in the top of member 28 form the inlet and outlet, respectively, 75 for the cooling medium for the motor. It will, therefore, be evident that a constant circulation of said medium will take place through the hollow piston rod 17 and piston 20.

80 Located on the face of cylinder head C is a hollow, valve protuberance 33^a, Figs. 4 and 5, having a spring seated internal inlet valve 34 and an opening 35, to which the usual type of carburetor (not shown) may 85 be attached by suitable fittings. Adapted to reciprocate in cylinder A is a trunk piston 36, connected to the crank shaft 10 by a suitable connecting rod 37. Fastened to hollow piston rod 17, intermediate, the 90 stuffing boxes 19 and 29 and is a cross head 38, extending diametrically beyond the outline of cylinder A, as clearly seen in Fig. 4. At the free, opposite ends of this cross head are pivoted depending 95 connecting rods 39 and 40, the lower ends of which rods are connected to the free 100 ends of rocker arms 41 and 42. The opposite ends of these rocker arms are keyed or otherwise rigidly fastened to the oscillatable shaft 12, already referred to, which 105 is supported in journals 11 and 11^a on crank case B. Medially of the length of rocker arms 41 and 42, are journaled rollers 43 and 44, which rollers contact with the 110 peripheries of cams 45 and 46, respectively, which cams are fixed on crank shaft 10. These cams have each the following characteristics and operate in unison: a dwell for 115 180 degrees at the point of greatest throw, a quick return to point of least throw for 90 degrees, and an accelerating advance to the point of greatest throw for the remaining 90 degrees of the circle. Said cams are fastened to crank shaft 10 in such a position that the dwell will begin approximately 120 30 degrees in advance of the crank in the direction of revolution. In order to maintain the rollers 43 and 44 in contact with the cams 45 and 46, I surround shaft 12, Fig. 4, with a substantial helical spring 125 47, under heavy tension, one end of said spring being fastened to journal bearing 11 and the other firmly fixed to shaft 12, so that the tendency of said spring will be to 130

depress the outer or free ends of the rocker arms 41 and 42. It will now be observed that the revolution of the crank shaft will result, through the action of cams 45 and 5 46, rollers 43 and 44, rocker arms 41 and 42, connecting rods 39 and 40, cross head 38, and piston rod 17, in the intermittent motion of the secondary piston 20, as hereinbefore outlined.

10 I now call attention to the fact that my type of construction may be applied to either vertical or horizontal engines, and to multi-cylinder motors, as well, without change or modification.

15 While herein I have disclosed the preferred mode of practising my invention, I wish it understood that I may make changes or alterations therein without departing from the spirit or scope thereof, so long as 20 the elemental essentials are retained.

Having thus fully described my invention, I declare as new and desire to secure to myself by Letters Patent of the United States:—

25 An internal combustion engine including a cylinder having an inlet valve and an exhaust port, a base for supporting said cylin-

der, a crank shaft supported by the base, a working piston in the cylinder, means connecting the crank shaft and the piston for reciprocating said piston, a secondary piston in the cylinder, a piston rod for said piston and operable in one head of the cylinder, a spring pressed shaft supported by the base, rocker arms having one of their ends fixed to the shaft, a cross head fixed to said piston rod, arms pivotally connecting the cross head and the other ends of the rocker arms, cams rotatable with the crank shaft for operating the rocker arms to regulate the stroke of the secondary piston, said piston being provided with pressure actuated valves opening toward the working piston upon the return stroke thereof, thereby permitting a charge to pass from one side of said piston to the other, as and for the purpose set forth.

In testimony whereof, I have hereunto set my hand in the presence of two subscribing witnesses.

GEORGE WASHINGTON JONES.
